UNITED STATES PATENT OFFICE.

CARLO GAGLIAZZO, OF RONCO BIELLESE, ITALY.

TYPEWRITER.

1,420,998.

Specification of Letters Patent. Patented June 27, 1922.

Application filed April 3, 1920. Serial No. 370,914.

To all whom it may concern:

Be it known that I, CARLO GAGLIAZZO, a subject of the King of Italy, and resident of Ronco Biellese, Italy, have invented certain 5 new and useful Improvements in Type-writers, of which the following is a specification.

This invention relates to typewriters and has for its object a construction of type-10 writer in which the carriage holder may be easily removed for the purpose of substitution.

This invention has further for its object means for controlling the shifting of said 15 carriage holder and a construction of carriage and of paper holder mounted in the same allowing of removing this paper holder with paper therein from the carriage.

On the annexed drawing is shown by way 20 of example a construction of typewriter according to this invention and Figure 1 is a diagrammatic transverse section of a typewriter embodying this invention in which are omitted the parts which have no bearing 25 on this invention; Figure 2 is the plan view of the paper holder and Figure 3 is a side view of the carriage removed from the typewriter frame but in cooperation with a guiding part of the frame as hereinafter de-30 scribed.

As illustrated in Figure 1, the typewriter comprises a frame 1 having any required shape and in which are mounted the several devices for the operation of the typewriter. 35 On the drawing is illustrated the key device in connection with one key and associate type block but it is to be understood that the number of keys, type blocks and associate devices may be any desired one.

40 Said key device comprises a lever 2 connected by a rod 3 with a lever 4 pivoted at 5 and having a hammer or block 6 provided with types intended to strike the paper.

The frame 1 of the typewriter is provided 45 with uprights 7 carrying pins or a trans-verse rod 8 to which is hinged the carriage holder.

This carriage holder comprises a guide bar 9 provided with a number of hooks 11 50 adapted to engage said pins 8 and with controlling arms 10 adapted to be controlled by the shift key as hereinafter described. On said guide bar 9 is mounted to slide, by means of balls 23, a frame 22 having end 55 plates 24 which form the sides of the car-

riage and in which is mounted the paper holder hereinafter described.

Each arm 12 solid with guide bar 9 is engaged by a rod 13 carried by levers 14 pivoted at 15 at each end of the type frame; each 60 lever 14 is controlled by a rod 16 connected with the arm 17 of a crank lever 18 pivoted at 19 and whose other arm 20 is provided with the shift key 21.

The paper holder which is supported by 65 end plates 24 of the carriage consists of a frame (Figure 2) comprising two end plates 25 (see Figures 2 and 3) interconnected by bars 26; in said frame are mounted the platen roller 27 and the pressure rollers 28 70 intended to hold the paper on said platen roller.

The shaft 29 of the platen roller is pivoted in plates 25 and is provided with usual and known means for rotating said roller either 75 by hand or automatically at the end of each line.

Further said shaft provides two journals 80 adapted to seat in seats or recesses 31 provided by the end plates 24 of the carriage.

The paper holder frame is provided with a lower rod 32 engaged in a stationary U-shaped fork 33 secured on the frame 1; the recess of said fork is open at its top portion 85 and provides two vertical guiding surfaces contacting with said rod 32.

On the carriage frame 22-24 is mounted the rack bar 34 meshing with a pinion 35 which is controlled by a pawl device in such 90 a manner as to rotate to the extent of one tooth at each operation of one of the keys so as to allow the progression of the carriage to one space after a type has been impressed on the paper. This pawl device is well 95 known and therefore it is not described and illustrated.

Said rack bar 34 is mounted on the carriage frame by means of pivots 37 and is controlled by a lever 36 having an end 38 100 adapted to be operated by the finger for the purpose of releasing said rack bar from the pinion 35 and associate pawl device and thus obtaining the free motion of the carriage.

The construction according to this invention allows of removing in an easy manner 105 the carriage holder with the carriage from the typewriter for the purpose of using at will on the same typewriter a number of carriages having different lengths; for this 110

purpose the carriage holder 22—24 is lifted to disengage its hooks 11 from rod 8 to which they are hanged, this being allowed by the shape of hook 12 engaging the controlling rod 13 and then it is easily removed from the typewriter and another carriage holder and carriage having any desired length is substituted for it.

The above described construction 10 proves the operation of the typewriter as it allows of using a carriage guide bar 9 having a proper length in connection with each carriage so that each of the carriages of different lengths which may be used on the 15 typewriter is always truly guided in its motion.

Also the paper holder frame with platen and pressure rollers may be removed as a 20 whole from the carriage so that it is possible to remove at any time from the typewriter said paper holder with a number of paper sheets and interposed carbon paper sheets and to substitute for it another paper holder to write on other sheets and finally 25 to replace in the typewriter the first paper holder.

For this purpose the paper holder is merely lifted from its supporting brackets or carriage side plates 24 to disengage the 30 journals 30 from seats 31 and rod 32 from guiding fork 33; thus the paper holding frame comprising side plates 25, connecting rods 26 and platen and pressure rollers 27 and 28 may be removed as a whole from the 35 carriage.

Another important feature of this invention consists in the operation of the carriage holder and carriage in connection with shifting of carriage under the operation of 40 the shift key intended to obtain the impression of either of types carried by each type block.

As shown on the drawing each type block 6 is provided with two types and the carriage is controlled by a shift key 21 to carry the impression line of the platen roller 27 in register with either of said types.

In the position illustrated on the drawing the platen roller is in position to obtain 50 the impression of the lower one of the types provided on the type block 6. When it is desired to impress the upper type the shift key 21 is shifted and thus levers 14 are shifted to left by means of crank lever 55 20—17 and of rod 16, and therefore the arms 10 and carriage guide bar 9 are rocked to left around axis of pivots 8 together with paper holder and platen roller.

In this motion the paper holder is moved 60 from a lower position in which the centre of the platen roller is at A to an upper position in which the centre of said platen is at B, but said paper holder and platen roller are loosely supported by the brackets 24 and 65 are slidably engaged by the rod 32 with the

U-shaped guide 33; then during the clockwise rotation of the brackets 24 around pins 8 through the angle required for the shift, the holder 25 and platen 27 are prevented from rotating as a part solid with them, that 70 is, they are caused to rotate counterclockwise with regard to said brackets through the above stated angle. Thus the same generatrix of the platen which by the position A of the platen roller was in condition to be 75 struck by the bottom type is now in condition to be struck by the top type of the block 6, and it is obtained that the types of either row may be written on the same true horizontal line. At the same time, by this 80 construction, the platen portion struck by the types is tangential with substantially parallel planes in both positions of the shift and therefore the types of the block may be flat. This is a great advantage over the 85 constructions in which the striking surface of the types must be shaped to follow the cylindrical shape of the platen.

The above described operation of the paper holder and platen roller may be briefly defined as causing said parts to be held parallel to their initial position during their oscillation with the carriage and carriage carrier for type shifting purposes.

A further advantage of the arrangement 95 according to this invention is that it allows of locating the rack bar 34 in such a position as to be always in engagement with the cooperating pinion during the shifting of the carriage and carriage holder, said 100 rack bar being located at a proper distance from the axis of oscillation of the carriage holder so that it moves along an arc which practically corresponds to a straight line; by this construction it is no longer necessary to arrange the pinion 35 to move longitudinally with regard to the bearings of 105 its shaft for the purpose of holding it in engagement with the rack bar 34, as required in some of the known constructions.

By this construction the pinion 35 may be made solid with its shaft and this latter may be pivoted in stationary bearings provided that said pinion has a suitable length to mesh with said rack bar in all positions 110 taken up by the same when the carriage holder is shifted by the operation of the shift key.

What I claim as my invention and desire to secure by United States Letters Patent is:

1. In a typewriter of the kind having type blocks each provided with a plurality of types, a stationary frame, pivoting means in said frame, a carriage carrier removably hung upon said pivoting means, and controlling means for shifting said carriage carrier around said pivoting means to obtain the impression of either of said types, said controlling means being removably engaged by said carriage carrier.

2. In a typewriter of the kind having type blocks each provided with a plurality of types, a stationary frame, pivoting means in said frame, a carriage carrier mounted in a removable manner on said pivoting means, controlling means for rocking said carriage carrier around said pivoting means to obtain the impression of either of said types, said controlling means being removably engaged with said carriage carrier, a carriage mounted to slide along said carriage carrier, a paper holder freely supported in said carriage and cooperating means on said stationary frame and paper holder for holding said paper holder substantially parallel to its initial position during the rocking of said carriage carrier and carriage for the type shift. 35
3. In a typewriter of the kind having type blocks each provided with a plurality of types, a stationary frame, pivoting means in said frame, a carriage carrier mounted in a removable manner on said pivoting means, controlling means for rocking said carrier around said pivoting means to obtain the impression of either of said type, said controlling means being removably engaged with said carriage carrier, a carriage mounted to slide along said carriage carrier, a paper holder comprising a frame in which are mounted the platen and pressure rollers, said paper holder being removably supported in said carriage, a fork shaped guiding member in said stationary frame and a bar 40
4. In a typewriter of the kind having type blocks each provided with a plurality of types, a stationary frame, pivoting means in said frame, a carriage carrier mounted in a removable manner on said pivoting means and carrying a carriage, controlling means for shifting said carriage carrier around said pivoting means to obtain the impression of either of said types, said shifting means being removably engaged with said carriage carrier, a rack bar mounted in said carriage carrier, and a controlling pinion meshing with said rack bar in all positions of said carriage carrier. 45
5. In a typewriter of the kind having type blocks each provided with a plurality of types, a stationary frame, pivoting means on said frame, a carriage carrier mounted in a removable manner on said pivoting means and carrying a carriage, controlling means for shifting said carriage carrier around said pivoting means to obtain the impression of either of said types, said shifting means being removably engaged with said carriage carrier, levers pivoted in said carriage and carrying a rack bar, and a controlling pinion meshing with said rack bar in all positions of said carriage carrier. 50

Signed at Turin, Italy, this 27 Feb., 1920.

CARLO GAGLIAZZO.
